ROCK BIT

Alfred C. Catland, Alhambra, Calif., assignor to
Globe Oil Tools Company, Los Nietos, Calif.,
a corporation of California

Application June 22, 1938, Serial No. 215,145

6 Claims. (Cl. 255—71)

This invention relates to well drilling tools and relates more particularly to bits for use in the rotary method of well drilling. A general object of this invention is to provide a sturdy long-wearing and effective rock bit or roller bit.

Another object of this invention is to provide a rock bit of increased strength and improved operation.

Another object of this invention is to provide a rock bit that is economical to construct by reason of the simplified and reduced machine work involved in its manufacture.

Another object of this invention is to provide an improved rock bit in which the pins or supports carrying the outer roller cutters are integral with the bit body thereby eliminating joints at highly stressed points and increasing the rigidity of the bit.

Another object of this invention is to provide a rock bit in which the central bridge or web is a separately formed part greatly simplifying the machine work on both the bit body and the bridge or web.

Another object of this invention is to provide a rock bit embodying large flanges or washers joined with the central web and serving to effectively seal the inner ends of the outer cutters against the entrance of the well fluid and cuttings and aiding in the transmission of pressures and forces between the cutter supporting pins and the web.

A further object of this invention is to provide an improved rock bit embodying bearings for the roller cutters involving a minimum number of parts securely locked against vibration.

The various objects and features of my invention will be fully understood from the following detailed description of a typical preferred form and application of the invention, throughout which description reference is made to the accompanying drawings, in which:

Fig. 1 is a side elevation of the improved bit of this invention with the lower portion broken away to show the central web and the outer cutter assemblies in vertical cross section. Fig. 2 is an enlarged fragmentary detailed sectional view taken as indicated by line 2—2 on Fig. 1. Fig. 3 is a fragmentary vertical detailed sectional view taken as indicated by line 3—3 on Fig. 5. Fig. 4 is a fragmentary vertical detailed sectional view of the improved bit illustrating the inner and center cutters and their mounting means, and Fig. 5 is an enlarged fragmentary vertical detailed sectional view illustrating a pair of inner and center cutters and their mounting

means showing a part of the bearing member in side elevation.

The improved rock bit of the present invention may be said to comprise, generally, a body 10, a central bridge or web 11 secured to the body 10, outer roller cutters 12, means 13 rotatably supporting the outer cutters 12, sets or pairs of inner and center cutters 14 and 15 and means 16 rotatably supporting the sets of cutters 14 and 15.

The body 10 is adapted to be connected with the lower end of a rotary well drilling string. The upper end of the body 10 is provided with means for connection with the drilling string and the lower portion of the body is formed to receive the cutters 12, 14 and 15. In the typical case illustrated a tapered screw threaded pin 17 is provided on the upper end of the body 10 to facilitate the connection of the bit with the drilling string. A pair of diametrically opposite legs 18 is provided on the lower end of the body 10. The legs 18 project downwardly and outwardly from the body 10. The inner sides 19 of the legs 18 are generally flat and slope downwardly and outwardly with respect to the central vertical axis of the bit. A second pair of legs 20 is provided on the lower end of the body 10. The legs 20 are equally spaced between the legs 18 and are diametrically opposite. In the construction illustrated the legs 20 project downwardly and outwardly from the body 10 and the lower parts of the legs 20 are substantially vertical. The vertical lower parts of the legs 20 have flat substantially vertical inner surfaces or inner sides 22. The legs 18 and 20 are preferably integral with the body 10. A central fluid socket or passage 23 enters the body 10 from the upper end of its pin 17 and a plurality of ports 24 is provided in the body to discharge the circulation fluid from the lower end of the passage 23. The ports 24 may be lined with beans or nozzles 25 which direct the fluid downwardly against the cutters 12 and the cutters 14 and 15.

The bridge or web 11 is a spider-like element secured or joined to the body 10 to assist in carrying the cutter mounting means 13 and 16. The web 11 is an integral member and is formed separately or independently of the body 10. The web 11 comprises a central vertical part 26 and side parts 27 disposed transversely of and extending along the opposite edges of the central part 26. The web 11 is provided with a flat upper end which opposes a downwardly facing surface 28 on the lower end of the body 10. In accordance with the invention the upper end of the web 11

is secured to the body surface 28 by welding 29. The sides of the central web part 26 oppose the inner sides 22 of the legs 20. Bosses 30 are provided on the opposite sides of the web part 26 and project toward the opposing legs 20. The side parts 27 of the web 11 have downwardly and outwardly sloping faces 31 spaced from and opposing the inner sides 19 of the legs 18. The lower parts of the surfaces 31 slope outwardly at an increased angle. The web 11 is proportioned so that its lower end is in approximately the same plane as the lower ends of the body legs 18 and 20.

The web 11 being a separately formed member is easily and inexpensively machined, that is, its bosses 30 and its surfaces 31 are fully exposed and accessible prior to the attachment of the web to the body 10. Further, the inner sides 19 and 22 of the body legs 18 and 20, respectively, 20 and the other internal body surfaces are all easily accessible for machining before the attachment of the web 11 to the body.

The outer cutters 12 are tubular frusto-conical members rotatably supported between the legs 18 and the opposing web parts 27. The cutters 12 are provided to act on the outer portion of the well bore to cut the bore to gauge. Spaced peripheral cutting teeth 32 are provided on the outer cutters 12. The central longitudinal openings 33 of the tubular cutters 12 are of substantial diameter and the opposite ends of the cutters are flat and normal to the axis of their openings 33. The cutters 12 are arranged so that their large ends face outwardly and their small ends 35 face inwardly with respect to the vertical axis of the bit.

The means 13 for rotatably supporting the outer cutters 12 mount them between the legs 18 and the web parts 27 for rotation about downwardly and inwardly inclined axes. The means 13 include downwardly and inwardly projecting pins 34 on the legs 18. It is a feature of the invention that the pins 34 are integral with the body legs 18. The pins 34 being integral with the legs 18 eliminate joints between the cutter supporting means and the body legs 18 and directly transmit the forces and pressures from the bearing parts to the body legs. The pins 34 project downwardly and inwardly toward the central vertical axis of the bit and terminate in spaced relation to the surfaces 31 of the web parts 27.

The cutter mounting means 13 further include tubular bearing members 35 arranged on the pins 34 and received in the openings 33 of the outer cutters 12. The outer ends of the members 35 bear on the inner sides 19 of the legs 18 and have radial annular flanges 36. Welds 37a may fix the flanges 36 to the lower end portions of the legs 18 to prevent vibration of the bearing members 35 during the operation of the bit. The flanges 36 partially overlie or overlap the outer ends of the cutters 12 to close the outer ends of their openings 33. The flanges 36 serve to prevent the entrance of mud and cuttings into the outer ends of the cutter openings 33 and in the preferred construction the flanges 36 are partially inset or recessed in the outer ends of the cutters. The bearing members 35 are of sufficient length to project inwardly beyond the inner ends of the pins 34.

The cutter supporting means 13 are in the nature of anti-friction bearing means. Spaced annular ball races or grooves 37 are provided on each bearing member 35 and the walls of the

cutter openings 33 have similar grooves 38 opposing the grooves 37. Series of balls 39 are arranged in the sets of opposing grooves 37 and 38 to rotatably support the cutters 12 with a minimum of friction. The grooves 37 and 38 are of substantial depth so that the balls 39 are operable to transmit end thrusts in both directions, as well as radial thrusts, so that the balls may form the sole means for rotatably supporting the cutters 12 on the bearing members 35. Radial openings 40 are provided in the bearing members 35 and extend from their openings or interiors to their grooves 37. The openings 40 admit the balls 39 to the pairs of opposing grooves 37 and 38 during the assembling of the cutters on the bearing members. Plugs 41 occupy the openings 40 to prevent the escape of the balls 39 from the opposing grooves 37 and 38. The outer ends of the plugs 41 are shaped to be flush with and to conform to the walls of their respective grooves 37. The inner ends of the plugs 41 bear on the pins 34 to hold the plugs against inward movement. Means are provided for holding or keying the plugs 41 in place. Internal longitudinal grooves or key-ways 42 are provided in the bearing members 35 and keys 43 are provided on the inner ends of the plugs 41 to cooperate with the key-ways 42 to prevent turning and outward movement of the plugs.

The means 13 further include washers or nuts 44 on the web parts 27. The nuts 44 are rigid with the web parts 27 and may be formed integral with the web 11 or may be welded to the web surfaces 31 as at 45. The nuts 44 are washer-like elements of substantial diameter and cover or extend over substantially the entire inner ends of the cutters 12. The nuts 44 may be partially inset or recessed in the inner ends of the cutters 12. It will be apparent how the nuts 44 prevent the entrance of mud and cuttings to the inner ends of the cutter openings 33. The inner ends of the bearing members 35 preferably bear against the nuts 44. The nuts 44 may be thickened to have their central parts extend into the inner ends of the bearing members 35. Cap screws 46 are passed inwardly through longitudinal openings 47 in the legs 18 and their pins 34. The openings 47 are inclined downwardly and inwardly and are co-axial with the pins 34. The inner end portions of the screws 46 are threaded in the nuts 44 and the heads of the screws 46 are received in the outer parts of the openings 47. The screws 46 assist in attaching the web 11 to the body 10 and assume or assist in assuming certain of the forces on the cutter assemblies. The outer cutters 12 supported as just described are rotatable about downwardly and inwardly inclined axes and project downwardly and outwardly beyond the lower ends of the legs 18 to cut the well bore to gauge.

The inner cutters 14 and the center cutters 15 are provided to act on the formation at the inner portion of the well bore. The inner and center cutters 14 and 15 are provided in sets or pairs positioned at opposite sides of the central vertical axis of the bit, each pair including an inner cutter 14 and a center cutter 15. The inner cutters 14 are frusto-conical roller cutters having pitched peripheries and flat ends. The central longitudinal openings 48 of the inner cutters 14 are of substantial diameter and have reduced inner end parts. Suitable cutting teeth 49 are provided on the peripheries of the cutters 14. The inner cutters 14 are arranged with their large ends facing outwardly.

The center cutters 15 are located at the inner ends of the inner cutters 14 and are in co-axial relation with the inner cutters. The center cutters 15 are smaller in diameter than the inner cutters 14 and are preferably cylindrical. Spaced peripheral cutting teeth 50 are provided on the center cutters 15. The longitudinal openings 51 in the center cutters 15 are of the same diameter as the reduced inner portions of the openings 48 in the inner cutters 14. The openings 51 in the center cutters 15 receive the bosses 30 with slight clearance. Annular flanges or shoulders 52 are provided at the bases of the bosses 30 and are received in counter-bores of the openings 51. The shoulders 52 assist in preventing the entrance of mud and cuttings to the openings 51.

The means 16 for rotatably mounting the pairs of inner and center cutters 14 and 15 includes a single tubular bushing or bearing member 53 for each pair of cutters 14 and 15. The bearing members 53 extend through the openings 48 and 51 of the cutters 14 and 15, respectively, with suitable clearance having reduced inner portions received in the reduced inner parts of the openings 48 and in the openings 51. The inner ends of the bearing members 53 engage against the bosses 30 and the outer ends of the bearing members engage against the inner sides 22 of the body legs 20. Radial flanges 54 are provided on the outer ends of the bearing members 53. The flanges 54 overlap substantial portions of the outer ends of the cutters 14 and are preferably partially inset or recessed in the ends of the cutters. The flanges 54 aid in preventing the entrance of mud and cuttings to the cutter openings 48. Lugs 55 are provided on the flanges 54 and welds 56 secure the lugs 55 to the lower ends of the legs 20. The lugs 55 are formed to engage upwardly against the lower ends of the legs 20 and this engagement, together with the welds 56, prevents rotation of the bearing members 53. The bearing members 53 being welded to the body legs 20 are effectively held against vibration.

The means 16 is in the nature of an anti-friction bearing means operating to support the cutters 14 and 15 with a minimum of friction. A plurality of spaced annular ball grooves 56 is provided in the wall of the opening 48 in each cutter 14. Circumferentially spaced ball grooves 57 are provided in the bearing members 53 to oppose the grooves 56. In the form of the invention illustrated there are three sets or pairs of opposing grooves 56 and 57 for each cutter 14. Balls 58 are arranged in the opposing grooves 56 and 57 to rotatably support the cutters 14 on the bearing members 53. The grooves 56 and 57 are of such depth that the balls 58 transmit end thrusts in both directions as well as radial thrusts.

A pair of spaced annular ball grooves 59 is provided in the wall of the opening 51 of each cutter 15. A groove 60 is provided in each bearing member 53 to oppose the innermost groove 59 in the surrounding cutter 15. The grooves 60 are at the inner ends of the members 53 and have their inner sides open, as illustrated in Figs. 4 and 5 of the drawings. Annular ball grooves 61 are provided in the bearing members 53 to oppose the other grooves 59 in the cutters 15. Series of balls 62 are arranged in the opposing races or grooves 59 and 60 and 59 and 61 to rotatably support the cutters 15 on the bearing members 53. The opposing grooves 59 and 61 are of such depth that the balls 62 received in them are adapted to transmit end thrusts in both directions as well as the radial thrusts. The balls 62 in the grooves

59 and 60 are capable of transmitting outward end thrusts as well as radial thrusts. The corners of the bosses 30 may be ground off or cut away to have suitable clearance with the balls 62 engaged in the opposing grooves 59 and 60. The grooves 60 being open at the inner ends of the bearing members 53 allow the easy arrangement of the balls 62 in the opposing grooves 59 and 60 when the parts are assembled.

Radial bores or openings 63 are provided in the bearing members 53 and extend inwardly from their ball grooves 57. The openings 63 pass or admit the balls 58 to the registering grooves 56 and 57 when the cutters 14 are assembled on the bearing members 53. Plugs 64 occupy the openings 63 to prevent the escape of the balls 58 and the outer ends of the plugs 64 are shaped to conform with the walls of the grooves 57. A radial opening 75 is provided in each bearing member 53 to communicate with its groove 61. The openings 75 pass or admit the balls 62 to the opposing grooves 59 and 61 when the cutters 15 are assembled on the bearing members 53. Plugs 65 occupy the openings 75 and the outer ends of the plugs 65 are shaped to conform with the walls of the grooves 61.

Means are provided for preventing turning and outward movement of the plugs 64 and 65. An internal longitudinal key-way 66 is provided at each bearing member 53. Keys 67 are provided on the inner ends of the plugs 64 and cooperate with the key-ways 66. Similar keys 68 are formed on the inner ends of the plugs 65 and cooperate with the key-ways 66. The keys 67 and 68 engaged in the key-ways 66 prevent turning and outward movement of their respective plugs 64 and 65. The inner cutters 14 and the center cutters 15 are supported by bearing means in such a manner that thrust washers are unnecessary and the adjacent cutters are at all times free of one another.

The cutter mounting means 16 further includes a single supporting pin or shaft 70 for carrying the two bearing members 53. Horizontal or transverse openings 71 are provided in the two body legs 20 and a transverse opening 72 is provided in the web part 26 in axial alignment with the openings 71. The shaft 70 is arranged through or carried in the aligned openings 71 and 72. The shaft 70 extends through the tubular bearing members 53 to support the same. One end portion of the shaft 70 is threaded in one opening 71 and a head 73 is formed on the other end of the shaft and is received in the other opening 71. It will be apparent how the single pin or shaft 70 serves to support two cutter units or assemblies comprising the bearing members 53 and the cutters 14 and 15. The opening 72 in the web part 26 is co-axial with the bosses 30 and extends through the bosses to be of substantial length and to provide a maximum support for the intermediate portion of the shaft 70. The pin or shaft 70 cooperates with the inner ends of the plugs 64 and 65 to prevent inward movement of the plugs. In the preferred construction the bearing members 53 are formed and mounted so that the openings 63 and 75 are in their upper sides or portions. With this relationship of parts the walls of the grooves 57 and 61 at the openings 63 and 75 and the end parts of the plugs 64 and 65 are relieved of the heavier drilling forces.

The means 16 just described supports the inner cutters 14 for rotation about a horizontal axis and to project downwardly beyond the lower ends 75

of the body legs 20 so that they act on the formation at the bottom of the well bore. The center cutters 15 are supported by the means 16 to rotate about a transverse or horizontal axis and to project downwardly beyond the lower end of the web 11 to cut the central or inner part of the well bore.

It is believed that the operation of the bit provided by this invention will be readily understood from the foregoing detailed description. In operation the bit body 10 is secured to the lower end of a well drilling string and the string is rotated and fed downwardly in the usual manner. Circulation fluid is pumped down through the drilling string to discharge from the nozzles 25. This fluid flushes the cutters 12, 14 and 15 and maintains the necessary turbulence in the bottom of the well. The outer roller cutters 12 projecting downwardly beyond the body legs 18 cut the well bore to gauge and make an annular cut in the bottom of the well. The sets or pairs of inner cutters 14 and center cutters 15 act on the bottom wall of the well bore to drill the inner portion of the well.

The several cutters of the bit are supported by dependable anti-friction bearing means to rotate independently and with a minimum of friction. It is to be observed that the cutters are supported solely by balls and that thrust washers and roller bearings are not employed. The integral pins 34 on the body legs 18 with the assistance of the screws 46 and the web 11 serve to support the outer cutters 12. Each pair of inner and center cutters 14 and 15 is supported on a single integral bearing member 53. The members 53 being integral are strong and durable and are not subject to vibration.

Having described only a typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. A rotary well bit comprising a body having spaced integral downwardly projecting legs, inwardly projecting pins integral with the legs, a web at the lower end of the body having parts at the inner ends of the pin, welding securing the web to the body, roller cutters rotatably supported on the pins and having sockets in their inner ends receiving said parts whereby the inner ends of the cutters are closed by said parts, said pins having openings, and screws passed through the openings and threaded in said parts.

2. In a rock bit a body having a depending leg, an integral pin on the inner side of the leg, a depending web on the body, a rotatable roller

cutter on the pin, a nut welded on the web and extending across the inner end of the cutter, the leg and pin having an opening, and a screw extending through said opening and threaded in the nut. 5

3. In a rock bit a body having a depending leg, an integral pin on the inner side of the leg, a depending web on the body, a bearing member on the pin, a roller cutter, balls rotatably supporting the cutter on the bearing member, the pin having an opening, a nut on the web engaging the inner end of the bearing member and closing the inner end of the cutter, and a screw passed through the opening and threaded in the nut to connect the leg and web. 10

4. A well bit comprising a body having a pair of diametrically opposite legs, a web at the lower end of the body, welding securing the web to the body, nuts welded on the web and opposing the legs, pins integral with and projecting from the legs toward said nuts, bearing members on the pins between the legs and said nuts, outer roller cutters rotatably supported on the last mentioned bearing members, said nuts engaging over the inner ends of the outer cutters to close the same, 25 said pins having openings, and screws passed through the openings and threaded in said nuts.

5. In a rock bit, a body having a depending leg, a web at the lower end of the body, welding securing the web to the body, an integral pin 30 on the leg projecting toward the web, a tubular roller surrounding the pin and having a recess in its inner end, a part joined with the web received in said recess of the cutter and overlying the inner end of the cutter, a tubular bearing member 35 on the pin extending through the cutter from said part to the leg and partially receiving said part, a flange on the bearing member overlying the other end of the cutter to close the same, and anti-friction bearing elements rotatably supporting 40 the cutter on the bearing member.

6. In a rock bit, a body having a depending leg, a web at the lower end of the body, welding securing the web to the body, an integral pin on the leg projecting toward the web, there being an 45 opening extending through the leg and pin, a tubular roller cutter surrounding the pin, a part on the web entering the inner end of the cutter and overlying the inner end of the cutter to close the same, a bearing member on the pin between 50 said part and the leg, the central portion of said part being thickened to extend into the bearing member, a flange on the bearing member overlying the outer end of the cutter to close the same, anti-friction elements supporting the cutter on the bearing member for rotation, and a screw passed through said opening and threaded in the thickened central portion of said part. 55

ALFRED C. CATLAND.
